UNITED STATES PATENT OFFICE.

F. ANZ HEINRICH ALBERT, OF LODI, CALIFORNIA.

TURBINE-AIRSHIP.

1,041,942

Specification of Letters Patent. Patented Oct. 22, 1912.

Application filed October 16, 1911. Serial No. 654,891.

To all whom it may concern:

Be it known that I, FRANZ H. ALBERT, a citizen of the United States, residing at Lodi, in the county of San Joaquin, State of California, have invented certain new and useful Improvements in Turbine-Airships; and I do declare the following to be a full, clear, and exact description of the same, such as will enable others skilled in the art 10 to which it appertains to make and use the same, reference being had to the accompanying drawing, and to the characters of reference marked thereon, which forms a part of this application.

15 This invention relates to improvements in air craft of all kinds, and particularly to an air ship designed to be operated by turbine propeller, the object of the invention being to produce a vessel which will have a 20 tremendous velocity or air pressure below and above, whereby it will move forward and upward at great speed and in an accurate, direct manner without any danger of tipping either at the ends or sides.

25 A further object of the invention is to produce a simple and inexpensive device, and yet one which will be exceedingly effective for the purposes for which it is designed.

30 These objects I accomplish by means of such structure and relative arrangement of parts as will fully appear by a perusal of the following specification and claims.

In the drawing similar characters of reference indicate corresponding parts.

The figure in the drawing is a top plan view of the complete ship.

Referring now more particularly to the characters of reference on the drawing, I 40 first provide two cylindrical casings 1 spaced apart and suitably joined by connecting members 2, on top of which members 1 is disposed a deck or platform 3, provided with a suitable side railing 4. In 45 the top and bottom of the member 1 I provide a plurality of air doors or openings 5, provided with sliding shutters 6, whereby said doors 5 may be closed or opened in a manner as will be shown.

50 Within the cylindrical casings 1 I provide two turbine auger-shaped propellers 7 suitably mounted on shafts 8 having gears 9 connected by chains 10 with gears 11 on

a shaft 12 driven by a motor 13 mounted on the deck 3. The shutters 6 are provided 55 with rods 14 suitably connected by links and levers 15 with operating levers 16 disposed in front of the operator's seat 17, whereby the shutters may be opened or closed at will. When it is desired to rise, the members 7 60 are rotated by the motor in a rapid manner, which drives the air with great velocity through the rear of the members 1, which causes the ship to move forward and then the doors in the under side of the members 65 1 are opened, which drives the air with great velocity therethrough, and causes the ship to rise, the doors in the top being then closed. Then when it is desired to lower the ship again, the doors in the under side of the 70 members 1 may be closed and those in the top opened, and this will drive the air upward with great velocity and permit the ship to be lowered rapidly and still be under the control of the operator. 75

I provide a rudder 18 operated by cables 19 disposed around a drum 20 having an operating handle 21 for the purpose of turning the same one way or the other.

From the foregoing description it will 80 readily appear that I have produced such a device as substantially fulfills the objects of the invention as set forth herein.

While this specification sets forth in detail the present and preferred construction 85 of the device, still in practice such deviation from such detail may be resorted to as do not form a departure from the spirit of the invention as set forth herein.

Having thus described my invention what 90 I claim as new and useful and desire to secure by Letters Patent is:—

1. A device of the character described comprising two cylindrical members spaced apart, screw shaped turbine propellers turnably disposed in said cylindrical members, a motor for driving said turbines, said cylindrical members being provided with openings in the top and bottom, said openings being provided with shutters, and means for 100 closing or opening said shutters, as may be desired.

2. A device of the character described comprising two cylindrical members spaced apart, a platform secured on said members, 105 screw shaped turbine propellers turnably

2
disposed in said cylindrical members, a motor for driving said turbines, said cylindrical members being provided with openings in the top and bottom, shutters slidable over 5 said openings, rods connecting each set of said shutters, levers fulcrumed on said platform, links connecting said levers with said rods, links on the other ends of said levers,

and an operating lever connecting with said last named links, as described.

In testimony whereof I affix my signature in presence of two witnesses.

FRANZ HEINRICH ALBERT.
